United States Patent [19]

Tichy et al.

[11] Patent Number: Des. 315,429

[45] Date of Patent: ** Mar. 12, 1991

[54] HAIR CURLING IRON

[75] Inventors: **Edward Tichy**, Woodbury; **Richard B. Studley**, New Haven, both of Conn.

[73] Assignee: **Wahl Clipper Corporation**, Sterling, Ill.

[**] Term: 14 Years

[21] Appl. No.: 181,246

[22] Filed: Apr. 13, 1988

[52] U.S. Cl. D28/35

[58] Field of Search D28/35, 38;
132/223-232, 269; 219/222-226
